PORTABLE MICROWAVE OVEN OR SIMILAR ARTICLE

Thomas J. Binzer, Charles H. Schmitt, and Peter H. Wooding, Jefferson County, Ky., assignors to General Electric Company

Filed Aug. 26, 1970, Ser. No. 24,702

Term of patent 14 years

Int. Cl. D7—02

U.S. Cl. D81—4

The single figure of the drawing is a front perspective view of a portable microwave oven or similar article embodying our new design with the oven interior lighted.

Both the oven door at the left and the control panel at the right are furnished with full height and full width, lightly tinted glass fronts spaced ahead of recessed frames.

The side of the oven not shown is substantially like the side that is shown, and the back panel is flat and substantially plain.

It is to be understood that the perforations which are fragmentarily indicated on the inner panel continue across the surface thereof.

We claim:

The ornamental design for a portable microwave oven or similar article, as shown and described.
